SECURITY GUARD

Raymond U. H. Tegner, Lodi, Wis., assignor to
Amerock Corporation, Rockford, Ill.

Original design application Dec. 26, 1973, Ser. No.
428,363. Divided and this application Dec. 18,
1974, Ser. No. 533,962

Term of patent 14 years

Int. Cl. D8—07

U.S. Cl. D8—131

FIG. 1

FIG. 2

FIG. 3

FIG. 6

FIG. 4

FIG. 7

FIG. 5

FIG. 8

FIG. 9

FIG. 10

FIG. 11

FIG. 12

FIG. 13

FIG. 1 is a front view of a security guard incorporating my new design with the keeper plate for the guard on the left and the base plate for the guard on the right.

FIG. 2 is an end view of the keeper plate as seen from the left in FIG. 1.

FIG. 3 is an end view of the keeper plate as seen from the right in FIG. 1.

FIG. 4 is a side view of the keeper plate as seen from the bottom of FIG. 1.

FIG. 5 is a back view of the keeper plate.

FIG. 6 is a sectional view taken along the line 6-6 in FIG. 1.

FIG. 7 is a sectional view taken along the line 7-7 in FIG. 1.

FIG. 8 is a top view of the base plate.

FIG. 9 is a bottom view of the base plate.

FIG. 10 is a side view of the base plate as seen from the right in FIG. 1.

FIG. 11 is a back view of the base plate.

FIG. 12 is a sectional view taken along the line 12-12 in FIG. 1.

FIG. 13 is a sectional view taken along the line 13-13 in FIG. 1.

This application is a division of my co-pending application Ser. No. 428,363, filed Dec. 26, 1973.

I claim:

The ornamental design for a security guard, as shown.

No references cited.

WILLIAM N. WERTMAN, Primary Examiner
